UNITED STATES PATENT OFFICE

ARTUR BÜTTNER, OF HEIDELBERG, GERMANY, ASSIGNOR TO SCHNELLPRESSENFABRIK AKTIENGESELLSCHAFT HEIDELBERG, OF HEIDELBERG, GERMANY, A CORPORATION OF GERMANY

CYLINDER PRINTING PRESS

Application filed March 8, 1928, Serial No. 260,089, and in Germany October 27, 1926.

My invention relates to cylinder printing presses in which the printing members travel horizontally in opposite directions.

Various constructional forms of printing presses, in which the reciprocating motion of the form carriage and of the impression cylinder which travels along over it horizontally at the same time in the opposite direction are known. In these known constructions the reciprocating motion was produced by eccentrics, systems of levers and the like, which was the cause of considerable disadvantages, more particularly as it was not possible with the driving means used to maintain accurate working of the two oppositely travelling printing members.

It has also been proposed to cause the printing members to travel in opposition to one another in vertical direction, the motion being produced by racks fixed to the printing members and by toothed wheels. In such an arrangement the main function of the rack and pinion gear was to guide and support the considerable upwardly and downwardly moved masses. This arrangement of having the printing members arranged so as to move upwards and downwards vertically makes the printing press awkward to work and necessitates the rocking of some parts of the press out of the vertical working plane, which results in a complicated and expensive construction.

The present invention has for its object to provide in rapid printing presses, in which the printing members travel horizontally in opposite directions, a positive driving connection of the said printing members, so that even when the machine is running at high speed accurate registration will be maintained. The invention consists more particularly in this that the horizontally reciprocated form carriage is connected by power transmitting members positively to the carrier for the impression cylinder, which is also horizontally guided, and so arranged that through the motion of the form carriage in one direction the impression cylinder carrier will be moved in the opposite direction.

This can be effected by racks being fixed at both sides of the form bed and of the print-

ing cylinder carrier which are in continuous engagement with spur wheels journaled in fixed bearings on the machine frame.

In the accompanying drawings a constructional example of the invention is shown. 55

Fig. 1 being a partial side elevation of the machine, and

Fig. 2 a vertical section on line I—I of Fig. 1.

To a crank *a* on the crank shaft *a*¹ a connecting rod *b* is connected, the other end of which is linked by means of a bolt *a*² to bearing blocks *d* fixed to the under side of the form bed *c* which carries the printing form *c*¹. By this means the form bed *c* which is guided in well known manner in the machine frame *g* has a reciprocating motion imparted to it. In both sides of the form bed *c* are fixed by means of screws *e*² or the like the racks *e* and *e*¹ respectively, the teeth of which are 60 in accurate engagement with the spur wheels *f*. The latter are journaled on the stub shafts *f*¹ fixed to the machine frame *g*.

In the machine frame *g* the two side parts *i* with the bearings *i*¹ of the impression cylinder *k* are slidably guided in guide-ways *i*². These two side parts *i* are connected together by the cylinder axle *k*¹, which is fixed in them and on which the impression cylinder *k* can rotate. To the side parts *i* are fixed by means 70 of screws *h*² or the like the racks *h* and *h*¹ respectively, which are also in continuous engagement with the spur wheels *f*.

With the arrangement described, when the form bed *c* has a reciprocating motion imparted to it by the connecting rod *b* the racks *e* and *h* and the intermediate spur wheel *f* will cause the printing cylinder support *i* with the printing cylinder *k* to travel through the same distance and at the same velocity, 80 but in the opposite direction. While the printing cylinder *k* is travelling over the form bed *c* from the position shown in Fig. 1, the printing cylinder will perform a revolution. 90

I claim:—

In a printing press the combination of a machine frame, horizontally arranged guide-ways in said frame, a form bed reciprocating on said guide ways, means for moving said 100

form bed, and a toothed rack fixed on either length side of said form bed, a horizontally arranged guide way on each length side of said machine frame, two side parts carrying the impression cylinder and sliding on and supported by the last said guide ways, an axle connecting said two side parts, said impression cylinder being turnable on said axle, a toothed rack firmly connected to each of said two side parts, a fixed bearing provided on either length side of the machine frame, and a toothed wheel journaled in each bearing, said toothed wheels being arranged between and engaging the toothed racks on said form bed and impression cylinder side parts, substantially as and for the purpose set forth.

In testimony whereof I have affixed my signature.

ARTUR BÜTTNER.
